HEATING SYSTEM FOR LIQUID CIRCULATING COOLING SYSTEMS

Oscar A. Ross, New York, N. Y.

Application August 9, 1928. Serial No. 298,434

9 Claims. (Cl. 123—174)

This invention refers to internal combustion motors and more particularly to that class having a liquid circulating cooling system usually associated therewith.

When initially starting motors of this type it is customary to choke, or prime the motor resulting in supply of excess of fuel thereto, this fuel, in known manner, causing dilution of the lubricating oil, as well as depriving the cylinders of adequate lubrication during the starting period of the motor.

The prime object of this invention is to provide a means for rapidly heating the cooling liquid of the motor whereby a temperature approximating that of normal operating conditions said motor will obtain.

Other objects and advantages will appear as the description of the invention progresses, and the novel feature of the invention will be pointed out in the appended claims.

This invention consists in the novel construction and arrangement of parts hereinafter described, delineated in the accompanying drawing, and particularly pointed out in that portion 25 of this instrument wherein patentable novelty is claimed for certain and peculiar features of the apparatus, it being understood that, within the scope of what hereinafter thus is claimed, diverse changes in the form, proportions, size 30 and minor details of the structure may be made without departing from the spirit of, or sacrificing any of the details of the invention.

In describing the invention in detail, reference is had to the accompanying drawing, wherein I 35 have illustrated embodiments of my invention, and, wherein like characters of reference, designate corresponding parts throughout the several views and in which:—

Figure 1 is a front elevational view taken on line 1—1 of Fig. 2 and Fig. 2 is a side elevational view taken on line 2—2 of Fig. 1, and Fig. 3 is a side elevational view of an automatic steam generator, and Fig. 4 is a sectional view of a valve taken on line 4—4 of Fig. 5, and Fig. 5 is a front 45 elevational view of the same valve taken on line 5—5 of Fig. 4, and Fig. 6 is a sectional view of a modified form of valve, and Fig. 7 is a side elevational view of a valve showing a modified coupling therefor, and Fig. 8 is a side elevational 50 view of a control valve associated with the steam generator.

Referring to Figs. 1 and 2, showing an internal combustion motor and a liquid cooling system therefore to which applicant's improved heating system is applied, the motor 1, shown

as supported in a motor vehicle 2, has its circulating liquid cooled by radiator 3 having inlet connection 4 and outlet connection 5 connected therebetween. Secured preferably opposite the flow connection 6 and on the front and accessible side of the radiator 3, is a valve 7, more fully hereinafter described.

Referring to Fig. 3, illustrating an automatic steam generator 10 wherein the pressure of the steam controls the supply of heat thereto whereby a substantially uniform pressure of steam indicated by gage 11 may be maintained within said unit, to the steam outlet 12 is secured a quick operable valve 13 controlled by handle 14 and to the outlet of which is secured 60 one end of hose 15.

Secured to the sides of unit 10 are brackets 16—16 formed to provide spaces 17—17 into which hose 15 may be coiled when not in use.

Secured to the outlet end of hose 15 may also be secured a quick opening valve 18, more fully hereinafter described. Unit 10 is supplied with suitable handles 19—19 having a caloric insulation material covering 20 thereover whereby the unit may be transported without injury to 75 the hands from excess heating thereof.

Referring to Figs. 4 and 5, illustrating one form of valve 7, for attachment to radiator 3, body member 25 has flange 26 arranged to be secured to the core wall 27 of radiator 3, also 85 tubular extension 28, arranged to enter through orifice 29 in said wall to the interior of said radiator core and in contact with the cooling liquid therein.

Supported in canal 30 of body member 26, and arranged to be restrained to seat 31 by spring 32, allocated by nut 33, having outlet orifice 34, is valve 35 arranged when seated to close inlet orifice 36 formed in threaded extension 37 arranged to receive coupling 38 secured to hose 15.

Referring to Figure 6, illustrating a modified form of valve 40, which is similar to valve 7 however differs in that extension 41, extends more deeply into the cooling liquid chamber of radiator 3, and the exterior extension 42 has an internally threaded position 43, a guide bore 44, and a concave seat 45, against which the concave nose 46 of modified coupling 47 is arranged to impinge. Exterior extension 42 is also formed with a lug 48 to which cover 49 is hinged by pin 50, a suitable spring (not shown) acting to restrain said cover over said extension.

Referring to Fig. 7, the modified valve 55 is similar to valve 7 however the threaded extension 37 thereof is modified to have a smooth ex-

terior extension 56 in which are suitably secured bayonet pins 57-57.

Referring to Fig. 8, illustrating a combined valve and coupling 60 for attachment to the discharge end of hose 15, the valve member 61 is preferably of the rapid openable type having spring returned valve stem 62 arranged to be depressed by handle 63 hinged to lug 64 by pin 65. Swivelly secured to the outlet end of valve 61 is coupling member 66, having swivel 67 communicating through tubular member 68 to coupling member 38, a sleeve 69 of caloric insulating material acting to calorically insulate said part. A similar caloric insulating sleeve 70 is secured over the discharge end of hose 15, said sleeves acting to prevent heat injury to operators.

The handles 14 and 63 are preferably also covered with a sleeve formed of caloric insulation material (not shown).

The operation of the system is as follows:— When a motorist desires to start his automobile on a cold morning the coupling, as 38, is attached to valve 7 whereafter the valve 14 or 25 valve 61, which ever may be employed, is opened by depressing handles 14 or 63. Simultaneously steam passes from steam generator 10, through hose 15 to valve 7, the pressure thereof restraining valve 35 away from seat 31 thereby 30 permitting said steam to pass through canal 30 and orifice 34 to the cooling liquid in radiator 3 where it is condensed, said condensation acting to raise the temperature of said liquid in known manner.

35 It will be noted that the valve, as 7, is preferably placed opposite the outlet fitting 6, therefore as the steam is injected into the cooling liquid through orifice 34, said liquid is, by injector action, restrained to pass into connection 40 5 and thence to the circulating jacket of motor 1, thereafter passing through connection 4 to the upper portion of radiator 3 and thence downwardly therethrough to the valve 7 where it is again subjected to a further temperature 45 rise due to the injected steam from valve 7, whereafter it is again restrained to pass to motor 1 and complete the cycle hereinafter described.

On certain types of liquid circulating cooling system it is preferable to attach a valve as 7a on the cooling liquid jacket of the motor said valve being similar to any one of the forms of valve 7 and may be additional to the valve attached to the radiator 3 or may be solely employed for admitting steam to the system.

By employing a comparatively high pressure in steam generating unit 10, the temperature of the cooling liquid system of an internal combustion motor may be rapidly increased to the boiling point, said heated liquid acting to heat the motor cylinders and adjacent parts whereby said motor may be initially started without priming as is now customary in all forms of weather. Furthermore by thusly preheating the 65 circulating cooling liquid of internal combustion motors a motor car may be operated smoothly and at maximum capacity as it is initially placed in motion for service thereby increasing the economy and utility thereof.

70 Furthermore by preheating the circulating cooling liquid in the novel manner hereinafore described the condensed steam adds cooling liquid to the system in this manner automatically replacing the liquid evaporated during the previous day's operation of the motor.

When a large fleet of motor vehicles, as for example, motor trucks, or buses are to be initially started substantially simultaneously, steam generator 10 may be made a stationary unit in a remote part of the garage and the steam suitably piped to one or more convenient locations whereat hose connections as 15 are interposed for more conveniently supplying the steam to the cooling systems of the motor vehicles.

If desired steam generator 10 may be suitably mounted on a wheeled floor truck for more convenient transfer from one motor vehicle to another.

What I claim is:

1. A device for attachment to automobile radiators for supplying steam to heat the liquid therein comprising, a body member having a passageway extending therethrough between the ends thereof, one end of the member being in communication with the interior of the radiator and the other end thereof being positioned exteriorly of the radiator, a flange portion formed on the body member spacedly between the ends thereof arranged to be secured to the wall of the radiator, the flange portion surrounding the passageway, coupling means formed on the exteriorly positioned end of the body member arranged to matingly engage a member having correlated coupling means, and means associated with the passageway arranged to permit flow of steam therethrough into the radiator but prevent backflow of the liquid therefrom.

2. A device for attachment to automobile radiators for supplying steam to heat the liquid therein comprising, a body member arranged to be secured to the wall of the radiator, a rear portion formed on the member arranged in communication with the interior of the radiator, a forward portion formed on the member positioned exteriorly of the radiator body having coupling means formed thereon arranged to engage a member having correlated coupling means, a cover member hinged to the body member normally covering the coupling means arranged to be pivotally moved for exposing the coupling means, and a passageway extending between the rear and forward end portions having a valve therein arranged to permit flow of steam to the radiator interior but prevent backflow of the liquid therefrom.

3. A device for dispensing steam to a radiator included in the cooling system of an internal combustion motor comprising, a valve having a coupling member secured to the dispensing end thereof, a flexible conduit having a coupling member at one end thereof secured to the other end of the valve, caloric insulating members surrounding the coupling members between the ends thereof, and means operated at will for opening and closing the valve.

4. In apparatus for supplying steam to a cooling system for internal combustion motors, the system including inlet valves having a coupling portion, a flexible conduit having the inlet end thereof connected to a source of steam, a normally closed valve unit connected to the outlet end of the conduit, the valve unit having a quick detachable coupling portion thereon arranged to be coupled to the coupling of the inlet valves, and means for opening and closing the valve of the valve unit.

5. In apparatus for supplying steam to a cooling system for internal combustion motors, the system including inlet valves having a coupling portion, a flexible conduit having the inlet end

- thereof connected to a source of steam, a valve unit connected to the outlet end of the conduit having a coupling portion arranged to be coupled to the coupling portion of the system inlet valves, 5 a normally closed supply valve supported by the valve unit for normally preventing flow of the steam from the source, and a manually operated member for opening the supply valve upon establishing pressure thereagainst, the supply valve 10 being arranged to automatically close upon release of said pressure against the member.
6. In apparatus for supplying steam to a cooling system for internal combustion motors, the system including inlet valves having a coupling portion, a flexible conduit having the inlet end thereof connected to a source of steam, a quick detachable coupling member at the outlet end of the conduit arranged to be quickly detachably coupled to the coupling portion of the system 15 inlet valves, a normally closed supply valve controlling the flow of the steam from the source, and a member for opening the supply valve upon manually exerting pressure thereagainst, the supply valve being arranged to automatically close upon release of pressure upon the member.
7. In apparatus for supplying steam to a cooling system for internal combustion motors, the system including inlet valves having a coupling portion, a portable source of steam, a flexible conduit having the inlet end thereof normally connected to the source, a normally closed supply valve unit connected to the outlet end of the 20

- conduit, the unit having a quick detachable coupling portion thereon arranged to be coupled to the coupling of the system inlet valves, and means for opening and closing the valve of the valve unit.
8. In apparatus for supplying steam to a cooling system for internal combustion motors, the system including steam inlet valves having a mating coupling portion, a flexible conduit arranged to have steam from a source supplied to the inlet end thereof, a mating coupling member at the outlet end of the conduit arranged to be temporarily matingly connected to the mating coupling portion of the system inlet valves, a normally closed supply valve controlling the flow of the steam from the source through the conduit, and manually operated means for opening and closing the supply valve.
9. In apparatus for supplying steam from a source to a cooling system for internal combustion motors, the system including steam inlet valves having a mating coupling portion, a flexible conduit having the inlet end thereof normally connected to the source, a supply valve unit connected to the outlet end of the conduit having a normally closed supply valve, a mating coupling portion on the unit arranged to be temporarily matingly connected to the mating coupling portion of the system inlet valves, and manually operated means for opening and closing the supply valve.

OSCAR A. ROSS.
